UNITED STATES PATENT OFFICE

EARL W. LITTLE, OF INDIANAPOLIS, INDIANA

CAGE CONSTRUCTION

Application filed July 30, 1929. Serial No. 382,194.

This invention relates to cage structures and particularly to bird cages and one feature of the invention is the manner and means for anchoring the crown forming ends 5 of the cage forming wires.

A further feature of the invention is in so arranging the anchoring ends of the wires that the wires will be under more or less tension whereby the wires will be held in 10 true alignment and uniformly shaped under all conditions.

A further feature of the invention is the provision of means for securing the various parts of the cage structure together in uniform spaced relation and in a manner to reinforce the wires.

A further feature of the invention is in so constructing the anchoring ends of the wires that the wires will remain in true assembled 20 position until they are permanently secured together.

A further feature of the invention is in so anchoring the ends of the wires that they will be forced to bend in uniformity throughout the extent of the cage structure when being shaped into cage form.

Other objects and advantages will be hereinafter more fully set forth and pointed out in the accompanying specification.

30 In the accompanying drawings which are made a part of this application,

Figure 1 is a fragmentary top plan view of wires assembled for forming a cage.

Figure 2 is a transverse sectional view 35 thereof, with the ends of the wires in anchored position.

Figure 3 is a similar view showing the ends of the wires prior to being anchored together.

40 Figure 4 is a transverse sectional view through a modified form of cage structure.

Referring to the drawings in which similar reference numerals designate corresponding parts throughout the several views, the 45 numeral 1 designates the wires employed for

forming the body of a cage, the upper ends of said wires having hook terminals 2 adapted to engage with a ring like plate 3, that portion of the wire passing over the plate 3, preferably resting on the face of the plate, 50 while the terminus of the hook member 2 is normally positioned a distance from the under face of the plate to form a pocket for receiving a quantity of the solder or other medium employed for securing the wire to 55 the plate, and thus very rigidly anchoring the wires to the plate.

In applying the solder, the wires, are first placed in hooked relation with the plate 3, 60 with the terminals 2 drawn taut against the inner edge of the plate, after which a quantity of solder 4 is placed on the wires substantially in the manner shown in Fig. 3 and a blow torch or other means applied for melting the solder. As the ring of solder is 65

melted it flows between the assembled wires and onto the plate 3 and anchors the wires thereto as well as secures the wires together for a distance, thus greatly reinforcing the wires and causing them to bend in uniformity 70

when the wires are formed into a cage structure. The metallic nature of the ring like plate 3 and the wires 1, attracts the solder as 75

it is melted, so that as the blow torch is applied, the solder will travel a distance in either direction from the fusing point and enter and substantially fill all crevices at 80

points between the wires and the plate, thus making said parts integral and forming an extensive anchoring surface and one that cannot be easily torn loose or otherwise weakened from usage.

In Figure 4 of the drawings, a different form of cage structure is shown and in this form of device, the hook terminals 5 engage a 85 vertically extending flange 6 of an anchoring plate 7, so that when the wires 8 are shaped into cage formation, a downward pull will be made against the flange 6, while with that form of structure shown in Figs. 1 and 2, an 90

outward pull will be made against the plate 3. The termini of the hook like terminals shown in Fig. 4 will rest against the inner face of the flange 6 while the wires 8 are spaced from the outer face of the flange, thus leaving a pocket or space 9 exteriorly of the flange for the accumulation of solder, this accumulation being between the wires proper and the flange, instead of between the termini 10 of the terminals 2 and the plate 3, as in the other form of cage structure.

By anchoring the ends of the wires as herein shown, they will be very rigid at their secured ends, which is very essential in properly maintaining the wires uniformly spaced and shaped when they are bent into cage formation, thus insuring uniformity in the curvature of the crown portion of the cage, with no unsightly bulges or other deformities therein.

It will likewise be seen that by providing the hook terminals at the ends of the wires, said wires can be very quickly and accurately assembled prior to the soldering operation and that the wires will remain in accurately spaced relation during the soldering operation. It will further be seen that by providing the elongated soldered surface, that part of the cage receiving the major strain thereon, incident to suspending the cage from a support, will be thoroughly reinforced and braced, thus preventing the cage being drawn out of shape from usage.

While I have illustrated in a general way, certain instrumentalities which may be employed in carrying my invention into effect, it is evident that many modifications may be made in the various details, without departing from the scope of the appending claims, it being understood that my invention is not restricted to the particular examples herein described.

What I claim is:

1. In a cage structure, an anchoring ring, a plurality of wires associated therewith, hook like terminals on the wires adapted to engage said ring, said wires and terminals being arranged to fit closely against one face of said ring and form a pocket like space on the opposite face thereof, and a fusible soldering means applied thereto in a manner to cause the soldering medium to enter the spaces between the wires and said ring and accumulate in and substantially fill said pocket like space.

2. In a cage structure, an anchoring member, wires having hook like terminals adapted to be projected over and drawn into engagement with said anchoring member, said terminals being arranged to form a pocket like space on one face of said anchoring member, and a fusible anchoring means applied over and adapted to enter the spaces between said wires and said pocket like space.

3. In a cage structure, an anchoring mem-

ber, a plurality of wires having hook like terminals adapted to be engaged in hooked relation with said anchoring member, and a fusible anchoring medium adapted to be fused over the anchored ends of said wires and enter spaces between said wires for soldering the wires to said anchoring member.

In testimony whereof, I have hereunto set my hand on this the 24th day of July, A. D. 1929.

EARL W. LITTLE.
